UNITED STATES PATENT OFFICE.

LAZARUS SHAPIRO, OF NEW YORK, N. Y., ASSIGNOR TO FREED-EISEMANN RADIO CORPORATION, OF BROOKLYN, NEW YORK, A CORPORATION OF NEW YORK.

ELECTROMAGNETICALLY-OPERATING LOUD-SPEAKING DEVICE.

Application filed May 28, 1926. Serial No. 112,340.

My invention relates more particularly to loud speakers, especially of the so-called cone type in which the sound vibrations are directly transmitted to the surrounding air 5 without the use of a horn or similar loading device usually employed with ordinary vibrating diaphragm loud speakers, the cone acting directly as the sound radiator.

My improvements relate to particular features in the electromagnetic unit as will appear from the following description.

In the drawings—

Figure 1 represents a transverse vertical central section thru the entire loud speaker 15 except the operating unit which is shown in side view;

Figure 2 represents in larger scale a small section of the rear rim portion of the cone showing the manner in which it is suspended 20 on its support;

Figure 3 represents a transverse section thru a suspension lug;

Figure 4 represents in longitudinal section and in larger scale the apex portion of the 25 cone;

Figure 5 represents a transverse section thru the cone chuck on the line 5—5, in Figure 4;

Figure 6 represents in larger scale a longitudinal section thru the operating unit on the line 6—6, in Figure 7;

Figure 7 represents a view of the unit shown in Figure 6 seen from the right-hand side, with the right-hand shank of the permanent magnet removed;

Figure 8 represents in larger scale a transverse vertical section thru the unit on the line 8—8, in Figure 1;

Figure 9 represents a top view of the unit 40 in larger scale;

Figure 10 represents a horizontal section thru the central portion of the unit on the line 10—10, in Figure 6;

Figure 11 represents in larger scale a detail of the armature movement; and

Figure 12 represents in perspective view the intermediate transmitting lever between the armature and the cone.

Referring to Figure 1, 1 represents a frame 50 provided with a hollow circular rim 2, which may for instance be made as a sheet metal stamping or the like, the frame being supported on a base 3 to which it is attached for instance by the bolt 4. The central portion 65 of the frame is suitably shaped to support the

electromagnetic operating unit 5 which will hereinafter be referred to as the unit, this unit being attached to the frame in any suitable manner for instance by bolts 6 which pass thru the U-shaped permanent magnet 60 7 of the unit. From the unit projects the driver rod 8 which is oscillated by the armature in a manner to be described presently, and the outer end of this driver rod is attached to the cone 9 which may be of any 65 suitable thin material such as for instance paper, veneer or the like. The driver rod 8 is adjustably attached to the apex of the cone preferably in a manner shown in Figures 4 and 5. It will be noted from these 70 figures that the spring chuck 10 is attached in a hole provided in the apex in the cone 9, for instance by spinning over the inner edge 11 of the chuck against an inner and outer shield 12 preferably of metal, so that the 75 cone material is held between these shields. The outer end of chuck 10 is longitudinally quartered by two central cuts at right angles to each other as clearly shown in Figure 5 so that the outer portion of the chuck 80 becomes yielding, a chuck nut 13 being threaded on the outer cone shaped portion of spring chuck 10, so that when this nut is tightened the jaws of the chuck are contracted thereby gripping the driving rod 8 85 located in the central bore of the chuck.

The rim of the cone has a double reverse bend as shown in Figure 1. The first reverse bend is denoted with 15 and the second reverse bend is denoted with 16. By these 90 means the rim of the cone is given sufficient stiffness to keep the shape of the cone. The cone is suspended merely for the purpose of sustaining its own weight, and to take its weight off the driving rod 8, by means of a 95 number of tension springs 17 which are attached at their outer ends to the inside of the hollow rim 2 of the frame and which are at their inner ends attached to the lugs 18 fastened to the cone near the edge of the first 100 reverse bend as shown at 19 in Figure 1. Figure 2 shows in detail the manner in which lugs 18 are attached to the cone, the lower portion 20 of lug 18 being attached, for instance by gluing, to the cone portion proper before 105 it makes its first reverse bend. The lugs consist of light material, for instance, as shown in Figure 3, of fabric 21 glued between two layers 22 of paper. The frame is provided near its central portion with a convenient 110

handle 23 partly shown in cross section in Figure 1.

The suspension of cone 9 by means of springs 17 as described, serving merely as a 5 positioning means for the cone relatively to the driving rod 8 of the unit and as a means for merely taking the weight of the cone off the driving rod, by no means serves and is not intended to serve as an abutment for the 10 rim of the cone. Quite to the contrary when in operation the entire cone together with its double reversed rim oscillates freely in the direction of its longitudinal axis, the slight tension of springs 17 constituting substantially 15 no impediment to such free oscillations. In other words, the neutral position of the cone when not in operation is not determined by the springs, or at least the slight effect these springs may have in determining 20 the neutral position is entirely negligible compared with the positioning effect on the cone in space which the driving rod 8 exerts, whose latter position substantially alone determines the neutral position of the cone in 25 the direction of its axis. This feature is quite important when comparing the cone suspension according to the present application with cones known in the prior art which are provided with a rim located substantially 30 in a plane at right angles to the longitudinal axis, and in which the outer edge of the cone rim is attached to a ponderous rim, so that when the cone is in operation the rim edge of the cone is stationary and so that the edge at 35 which the cone proper joins its own rim practically performs the maximum amplitude oscillations. In that case the normal position of the cone is largely determined by the cone rim, which, being fairly stiff, tends quite 40 strongly to maintain the cone in a central neutral position which, after the apex of the cone has been clamped to the driving rod, may not always coincide with the normal central position of the unit armature, in case ex- 45 pansion or contraction of the cone, due to the changes in temperature or humidity, occur. In those cases an undue stress is set up which, if not relieved before the cone is operated, is apt to give rise to distortion in the 50 sound reproduced. For example an initial stress in the outer rim is particularly harmful to reproduction of low frequencies, for which mass reactions are relatively unimportant and restoring force is the principal factor. 55 These disadvantages are entirely avoided in the cone suspension shown and described, on account of the practically negligible tendency of the peripheral springs to return the rim to a neutral position in the direction of the cone axis.

The unit which is shown in Figure 1 in full view is constructed as follows: Referring to Figures 6 and 9, it will be noted that the two ends of the U-shaped permanent magnet 7 60 have attached to them a laminated yoke 30

which consists of two halves, one half being attached to each leg of the permanent magnet 7 for instance by bolts 31. A gap is provided between the inner ends or poles D—E and D'—E' (Figure 6) of the yoke halves between which the armature is disposed as will be described presently. In order to conveniently hold the pack of laminæ, of which the yoke is composed, together, so that the manufacture in quantity is facilitated, a top plate 75 32 and a bottom plate 33 of non-magnetic material is provided which bridge the two halves of the yoke, each plate being provided with rectangular slots 34 (Figure 9) which engage with a press-fit protruding lugs 35 of 80 the yoke as may readily be seen from Figure 6. The two plates 32 and 33 are held together by two stay bolts 36 which are more clearly visible in Figures 7 and 8. By this arrangement not only are the laminæ tightly 85 held together but at the same time the gaps D—E and D'—E' are very exactly determined. The pole ends of the yoke halves are provided with inward lugs 37 clearly visible in Figure 6 which serve for centering the operating current coils 38 and 39 with relation to the gaps D—E and D'—E'. These coils, which may be connected in series or in parallel as the construction of the unit may require, may be conveniently inserted in place, 90 as shown in Figure 6, by holding the two coils together and inserting them into the yoke, their combined length being less than the distance between the lugs 37 appertaining to each yoke half. After the coils are inserted, 100 they are spread apart by means of wedges 40 so that they are seated over the respective lugs 37 and permanently held in place.

The armature 41 which is placed between the gaps of the yoke is of elongated diamond 105 shape as may be seen in detail in Figures 6 and 11, and is also composed of a suitable number of laminæ which are held together by small rivets 42. This shape is of particular advantage, because its greatest mass is 110 near its central portion where it least affects the frequencies at which the armature tends to oscillate, the outer tapered ends being comparatively thin and light, yet sufficient in cross section to carry the necessary magnetic 115 flux.

The armature laminæ are provided with a central transverse slot 43 into which, after the armature laminæ are assembled and riveted, a flat torsionally yielding bar 44 is 120 pressed which preferably consists of phosphor-bronze. Also this construction is of particular advantage for armatures of this type over prior constructions in which the yielding element, such as a flat bar, surrounds 125 the armature. In that case the alternating flux longitudinally traversing the armature is apt to set up eddy currents which encircle the armature in the bar, giving rise to not inconsiderable energy losses. When the bar passes 130

through the armature as shown here these currents cannot be set up.

The bar is visible in plan view in Figure 10 and, as will be noted from that figure, is 5 provided with a shoulder 45 against which the armature 41 rests after it has been pressed onto the bar. It may be noted that, for convenience of correctly assembling the armature laminæ so as to avoid the effect of slight 10 discrepancies in symmetry between the two ends of the armature which may have been caused by inaccuracies in the dies used for punching the laminæ, I have provided a small notch 46 (see Figure 11) on each lamina and 15 when the laminæ are assembled they are lined up so as to register at their notches 46, whereby all upper and lower ends of the diamond come together the same way as they are punched.

20 Armature bar 44 is disposed transverse to the plane of magnet yoke 30 and is supported at its two ends on studs which are attached to the non-magnetic end plates 32 and 33 of the yoke. As will be noted for instance from 25 Figure 8 one end of armature bar 44 is attached to a stud 50 fastened to the upper yoke plate 32, and the other end of the bar is attached to a stud 51 fastened to the lower yoke plate 33. In placing the armature bar on its 30 studs the armature is carefully centered so that its upper and lower end is symmetrically located in the air gaps D—E and D'—E' of the yoke.

By arranging the yoke and the armature of 35 the unit in the manner described I avoid entirely the passing of the flux produced by the operating current thru the shanks of the permanent steel magnet 7. The flux which prevails in this arrangement is as follows: The 40 permanent flux prevailing in the permanent magnet 7 for instance passes in the direction of the full line arrows from A over B into the laminated yoke arm by way of D', across the air gaps and the armature end to E' and over G in the direction of H. Also from A 45 by way of C, D, air gaps and upper armature end E, F, G, in the direction of H. With this flux prevailing and no operating current flowing thru the yoke coils 38, 39, it will be noted that the armature is completely balanced in its position in the yoke and no torsion is exerted on armature bar 44. If now 50 fluctuating operating current flows thru coils 38 and 39, the flux set up by these coils only travels thru the yoke, and taking one time instance of the flow, we may assume that it flows in the direction of the dotted line arrows. It would thus flow from B over C, D into the upper end of the armature, thru the 55 length of the armature to D' and back to B. Also from G to F, E into the upper end of the armature and thru its length to E' and back to G. Considering now that the permanent flux be in the direction as assumed hereinbefore, this permanent flux is at the time

instance of the operating flux assisted at D and opposed at E which would tend to throw that armature end to the left. In the lower portion of the yoke the reverse occurs, namely, the permanent flux is opposed at D' and assisted at E' which would tend to throw the lower end of the armature to the right. Thus the forces produced by the operating flux are effective simultaneously and symmetrically at both ends of the armature, tending to rock 70 it to and fro by distorting armature bar 40, which normally tends to return the armature into the central position shown in Figure 6.

The oscillations performed by the armature due to the operating current are transmitted to the cone as follows. As will be noted from Figures 8, 9 and 11 the outermost lamina 41^a on one side of the upper end of the armature is made of easy solderable material and this lamina is slightly outward bent and 80 curved at its end as shown at 60 and to the curved portion is attached, for instance by brazing, an operating rod 61 more clearly shown in Figure 11. This operating rod is brazed at its other end 62 to the free end of 85 an L-shaped reducing element 63. This element is shown in perspective view in detail in Figure 12 and consists of a flat portion 64 with outwardly turned edges 65 to give it the necessary stiffness, and of a base portion 66 90 likewise having outwardly turned edges 67 to give it the necessary stiffness. At the bent portion 68, no lateral out-turned edges are provided so that the element will yield at this portion to any bending forces applied at the 95 upper free end 62 when its lower or base portion 66 is held in fixed position.

It should be noted however that the lateral flanges 65 must extend very close to the bend 100 68, so that portion 64 may at no point be able 105 to whip in the direction in which rod 61 extends and vibrates. This might easily occur at higher tone frequencies if flanges 65 do not extend to the bend, and would thereby introduce energy losses and distortions.

The base portion 66 is attached to the lower yoke plate 33 by means of a screw 69, a small detent 70 provided at the end of base portion 66 engaging in a notch 71 punched into lower yoke plate 33 by which the turning of 110 the reducing element 63 on screw 69 is prevented. Portion 64 of this element has fixed to it intermediate its ends in suitable manner, for instance by brazing, the driver rod 8, the outer end of which is attached to the cone 115 apex as described at the beginning.

Over the driver rod is slipped preferably a piece of rubber tubing 73 which extends substantially the full length of driver rod 8 and tends to dampen the transverse vibrations which the rod 8 may be inclined to perform and which are apt to distort the sound produced.

The lead by which the operating current is supplied to coils 38 and 39 may be attached 125 130

to a binding post strip 75 attached to the permanent magnet 7 across its two shanks, the binding posts being shown at 76. The flexible current supply cord 77 is guided thru an eye 5 78 provided in the frame portion of the loud speaker and the entire unit is surrounded by a casing 79 by which it is protected from dust, the driver rod 8 carrying the rubber damper 73 passing thru a hole 80 out of the casing.

10 I claim:—

1. An electromagnetic sound reproducing unit having a laminated yoke comprising two halves facing each other with their pole ends and having gaps between opposing pairs of 15 poles and an armature disposed in said gaps, said yoke halves having lugs on the sides of their shanks and non-magnetic end plates having recesses to engage the lugs of opposing yoke shanks, thereby securing the exact 20 size of the gap between them.

2. An electromagnetic sound reproducing unit having a laminated yoke comprising two halves facing each other with their pole ends and having gaps between opposing pairs of 25 poles and an armature disposed in said gaps, said yoke halves having lugs on the outward sides of their shanks and non-magnetic end plates having recesses to engage the lugs of opposing yoke shanks thereby securing the exact 30 size of the gap between them, and stay bolts for holding said plates together.

3. An electromagnetic sound reproducing unit having a laminated yoke comprising two U-shaped halves facing each other with their 35 pole ends and having a gap between each opposing pair of poles and an armature disposed with its ends in said gaps, said yoke halves having lugs on the outward sides of their shanks and non-magnetic end plates 40 having recesses to engage the lugs of opposing yoke shanks, thereby fixing the spacing between opposing yoke poles, and stay-bolts for holding said end plates together, a torsionally 45 yielding bar supporting said armature freely within said yoke gaps and extending through said armature in the direction of the central transverse armature axis, one end of said bar being secured to one end plate and the other end being secured to the other end 50 plate.

4. An electromagnetic sound reproducing unit having a yoke comprising two halves facing each other with their pole ends and having gaps between opposing pairs of poles 55 and an armature oscillatingly supported intermediate its ends and being disposed in said gaps, said armature having an elongated diamond shape, the thin tapered ends of the armature being disposed in said gaps, and the 60 pole ends of said yoke halves being shaped to substantially follow the contour of said tapered ends.

5. An electromagnetic sound reproducing unit having a yoke, poles thereon, an oscillating armature extending between said poles 65

to conduct the magnetic flux between said poles, a yielding supporting bar extending through said armature transversely to its longitudinal axis to permit the armature to oscillate on said bar, said magnetic flux passing around both sides of said bar. 70

6. An electromagnetic sound reproducing unit having a yoke comprising two halves facing each other with their pole ends and having gaps between opposing pairs of poles, 75 and an elongated diamond shaped armature disposed with its thin tapered ends in said gaps to oscillate therein and adapted to conduct the magnetic flux between the yoke poles, a torsionally yielding bar of non-magnetic material passing thru the center of the armature in a direction transversely of the longitudinal armature axis, thereby oscillatingly supporting the armature, said magnetic flux passing symmetrically around both sides 80 of said bar. 85

7. An electromagnetic sound reproducing unit having a yoke, poles thereon, a laminated oscillatory armature extending between said yoke poles and means for oscillatingly 90 supporting said armature midway between said ends, said armature having the outermost lamina at one side consisting of an easily brazable metal, the end of said lamina being bent away from the armature body, and a 95 transmitting rod brazed to said lamina end for transmitting the oscillations of said armature.

8. An electromagnetic sound reproducing unit having an oscillating armature, a sound 100 radiator operated by said armature and a motion amplitude reducing means disposed between said armature and said radiator, said reducing means comprising an L-shaped lever element having lateral flanges at both 105 of its shanks, one shank being rigidly held, a transmitting rod fixed at one end to said armature and at the other end to the outer end of the free shank of said lever element, and an operating rod fixed at one end to said free shank intermediate its ends, and at the other end to said radiator, the flanges of said free shank extending close to the bend of the lever element to prevent whipping of the free shank during the oscillations. 115

9. An electromagnetic sound reproducing unit having a laminated yoke comprising two halves whose shanks face each other endwise to form opposing poles and having gaps between opposing pairs of poles and non-magnetic positioning elements extending across each pair of opposing shanks and engaging said shanks to fix and maintain the exact size of said gaps. 120

10. An electromagnetic sound reproducing unit having a yoke and poles thereon and an elongated armature element oscillatingly supported intermediate its ends and being tapered at both ends and disposed with said ends adjacent to said poles, said poles being 125 130

shaped to substantially follow the contour of said tapered ends.

11. An electromagnetic sound reproducing unit having a yoke and poles thereon and an elongated armature element, tapered at its ends and disposed across said poles to conduct the magnetic flux between said poles, a torsionally yielding bar of non-magnetic material passing through the center of said armature in a direction transversely of the longitudinal armature axis for oscillatingly supporting said armature, said magnetic flux passing symmetrically around both sides of said bar. ¹⁰
